UNITED STATES PATENT OFFICE.

JACOB REESE, OF PITTSBURG, PENNSYLVANIA.

ROLLING-MILL.

SPECIFICATION forming part of Letters Patent No. 268,825, dated December 12, 1882.

Application filed May 22, 1882. (No model.)

To all whom it may concern:

Be it known that I, JACOB REESE, a citizen of the United States, residing at Pittsburg, in the county of Allegheny and State of Pennsylvania, have invented a new and useful Improvement in a Continuous Train for Rolling Metals; and I do hereby declare the following to be a full, clear, and exact description thereof, reference being had to the accompanying drawings, forming a part thereof.

A continuous train is composed of a series of pairs of rolls, which are placed in front of each other, in order that the metal may pass from one pair of rolls into the next adjoining pair, and may be operated on by all of the rolls at the same instant. Continuous trains, as far as I am aware, have been used exclusively for the manufacture of spike-iron and wire rods. Attempts have been made to roll skelp-iron and hoop-iron on such a train; but I am informed that this has been abandoned. The great difficulty in adapting a continuous train for the production of hoop-iron or iron or steel of any shape which is to be sold as a finished article 25 I conceive to be in the fact that all continuous trains, as heretofore constructed, have been provided with so many gear-wheels and idlers, so as to have the rolls run at proper speeds and in the right direction, that the slip and back-lash incident to each tooth produced such an 30 irregular movement to the rolls as to make the iron passing through them of a wavy and uneven surface, which unfitted it for merchant sales; but when the metal was rolled into rods 35 and then cut up into spikes or drawn into wire these defects were not so objectionable. Another difficulty exists in the use of a continuous train for the manufacture of bars or hoops, which is that it is not practical to turn 40 the metal between succeeding pairs of rolls, and it has been proposed to alternate the tongue and grooved rolls from top to bottom of succeeding rolls; but this, when the tongue is in the bottom roll, throws the fin down, and 45 by rubbing against the bottom guide this fin is distributed over the bottom surface of the hoop, is rolled in at the next pass, and mars the appearance. Now, to obviate these difficulties and adapt the continuous train for the 50 manufacture of hoops and merchant bar shapes, I dispense with the use of cog-wheels, idlers,

and pinions, and in place thereof a series of pulleys are so arranged as to drive the rolls in the right direction and at the required differential velocities by the use of two endless belts, 55 or by retaining the pinions the train may be driven by one belt; and to obviate the difficulty of placing the tongue of tongue and grooved rolls as a bottom roll, I dispense with such rolls altogether, and in place thereof I 60 use box-grooves. Heretofore in the construction of box-grooves one half of the box-opening has been placed in each roll, which forms a fin in the center of the sides of the metal. Consequently each succeeding pass would 65 make the fin in the same place, and for this reason box-grooves have only been used where the blank so rolled could be afterward edged to roll down the fin; but with my improved box-grooves, in which the greatest part of the 70 metal is embedded in one roll and the less part in the other, the fin is above or below the center, and by reversing the position of the deep box-groove in each succeeding pass the 75 fin is rolled into the side of the metal, and the 80 surface of top and bottom is thus kept free from fin-slivers. To more fully provide for a clean surface, I employ guides with an open top and bottom, in order that the scale thrown off of the metal will drop down through the 85 guides, and thus prevent it from being rolled into the surface of the hoop. In lining up rolls for the purpose of making the metal thicker or thinner, it has been done by placing the liners between the necks of the top and 90 bottom rolls. It is a work of great danger to do this in any train, and especially in a continuous train while the train is in motion. To remedy this difficulty I form the housing-cap and the journal-box of the top roll in one 95 piece, by which arrangement I am enabled to line the top roll by placing liners between the top of the housing and the cap.

The object of my invention is to remove the difficulties which have heretofore prevented the use of a continuous train in the manufacture of hoop-iron, hoop-steel, and merchant shapes, and to so improve the train as to adapt it for rolling all kind of metal to advantage.

Referring to the drawings, Figure 1, Sheet 100 1, is a ground plan of my continuous train, in which no cog-wheels, idlers, or toothed pinions

are used. Figs. 2, 3, 4, 5, and 6, Plate 1, show the form of box-grooves and finishing-rolls of a continuous hoop-train, the greatest portion of the box being in the lower roll of Fig. 2, the upper roll of Fig. 3, the lower roll of Fig. 4, and upper roll of Fig. 5, Fig. 6 being plane-faced rolls. Fig. 7, Plate 1, shows the form of my open guide with a cross-section of the metal in place. Fig. 8, Plate 2, is a side elevation of Fig. 1. Fig. 9, 10 Plate 3, is a ground plan of a modification of my improved continuous hoop-train, in which cog-wheels and idlers are dispensed with, but in which pinions are used, and the rolls are placed on the necks of the pinions. Fig. 10, 15 Plate 4, is a side elevation of Fig. 9. Fig. 11, Plate 5, is a rear end elevation of Figs. 9 and 10. Fig. 12 is a side elevation of Fig. 11. Fig. 13, Plate 5, is a rear end elevation, and Fig. 14 is a side elevation, of Figs. 1 and 8.

20 Like letters refer to like parts.

I shall now describe my improvement as applied for rolling hoop-iron; but I wish it distinctly understood that I do not wish to limit the use of my improvement to that particular 25 branch of manufacture, but broadly claim its use in rolling metal of all kind.

Fig. 1, Sheet 1, exhibits a ground plan, and Fig. 8, Sheet 2, a side elevation, of my continuous hoop-train. It will be noticed that by 30 this arrangement I am enabled to dispense with all cog-wheels, idlers, and pinions. The rolls are driven by means of two endless belts working over pulleys which are placed on the ends of the rolls. The pulleys of each pair of 35 rolls are on opposite ends of the rolls, and the pulleys on each side of the train alternate from the top to the bottom roll of each succeeding pair. The arrangement of the belts and pulleys is fully shown in Fig. 8, Sheet 2. In order to keep the belts tight, the belt on one side 40 is passed down and over a tightening-pulley, while the belt on the other side of the train is passed up and over a tightening-pulley. These tightening-pulleys may be made adjustable in 45 the usual manner, so as to keep the belts at proper tension. The different pairs of rolls may be placed at any suitable distance from each other; but I prefer to have them so arranged that the pulleys will come near each other, in 50 order to have the belts cover as large a surface of each pulley as possible. This train is provided with my improved box-grooved rolls. In the first pair of rolls, a' , is the bottom roll, (see Sheet 1,) and has the larger portion of the 55 box in it, while a has the less portion of the box, and in each succeeding pair the largest portion of the box alternates from the bottom to the top and from top to bottom. Thus the rolls $a' b' c' d'$ have the least depth of grooves, 60 and the rolls $a' b' c' d$ have the deepest grooves of their respective pairs. The rolls a and a' are eight inches in diameter, b and b' are nine inches diameter, c and c' are ten inches diameter, d and d' are eleven inches diameter, and 65 e and e' are twelve inches diameter. The pulleys on $e e'$ are sixty inches in circumfer-

ence, on $d d'$ are seventy-three inches in circumference, on $c c'$ are eighty-eight inches in circumference, on $b b'$ are one hundred and six inches, $a a'$ are one hundred and twenty-six inches in circumference, and as the belt travels twelve hundred feet per minute, it will drive the several rolls so as to cause the metal to pass at the following speeds: $a a'$, two thousand seven hundred and thirty-four; $b b'$, three thousand six hundred and seventy-two; $c c'$, four thousand eight hundred and ninety; $d d'$, six thousand five hundred and one; $e e'$, eight thousand six hundred and forty inches per minute. The reduction of the area of the metal being twenty-five per cent., the velocity is correspondingly decreased from the driving-power.

The other arrangement or modification of my train is shown in Figs. 9 and 10. In it pinions are used, and the rolls made adjustable on the necks of the pinions, the pulleys being arranged so as to drive alternately the top or bottom of each succeeding pair of rolls.

The third feature of my improvement is in the peculiar form of the box-grooves employed. 90 By this arrangement the fins are continually rolled down into the edges, and as no fins are formed on the corners, a sounder-edged hoop can be made than when the work is done in tongued and grooved rolls. The guides are 95 also of the construction as shown at n in cross-sectional Fig. 7, which shows the guides with the metal in them. The object of using guides of this form is to allow the scale to drop out of the guides; otherwise it would be carried 100 into the succeeding rolls and mar and disfigure the blank and finished hoop; but by the use of the open guides the blank is guided by enclosing its edges only, and allowing the scale to drop, through the bottom, while the top is 105 open, so as to enable the roller to see how the metal is working, or to put water on it for the purpose of scaling it when desired. A continuous train of this class may be driven by means of a metallic belt, such as shown in Letters 110 Patent No. 251,377, granted to me December 27, 1881. In that case the pulleys need not have more than five-inch faces.

The advantages of this invention are, first, it does away with all gearing and cog-wheels; 115 second, the cost of construction and repairs is consequently reduced; third, double the amount of work may be produced; fourth, it dispenses with the rougher and catcher—two male experts—and this reduces the cost of labor; fifth, 120 the metal is worked more uniformly, and consequently better work will be produced; sixth, the improved box-groove will roll the metal with solid corners, and also roll down the fins into the edges, which I have never seen before.

125 It will be noticed that I construct the bearing of the top rolls and the cap of the housing in one piece. Thus by lining the cap I adjust the top roll at the same instant. In other words, instead of lining the rolls in the present 130 method between the bearings, as at x in Fig. 12, I line them at $x' x'$, same figure, Plate 5.

These journal-boxes may be made of cast-iron and babbittted; but they should be made with a water-jacket, such as fully set forth in application filed by me February 18, 1882, as by the use of the water-jacketed journal-box the

5 necks of the rolls will be kept cool at all times.

The power is applied at *e* and *e'*, they being the rolls requiring the greatest velocity. By applying the power at this point I am enabled 10 to place pulleys of an increasing diameter on each succeeding pair of rolls, and I am also enabled to reduce the diameters of each succeeding pair of rolls from the driving-power, thus concentrating the strain on and as near 15 to the driving-power as possible; and by communicating the power alternately from the top roll of one set to the bottom of the succeeding pair, and from the bottom to the top roll of succeeding pairs, I am enabled to turn each 20 roll in the proper direction without the use of idlers. This feature of my invention may be used on a continuous train in which cog-wheels are employed instead of belts.

Having thus described my invention, what I 25 claim, and desire to secure by Letters Patent, is—

1. A continuous train of rolls mounted in suitable housings, the rolls of each pair having pulleys on opposite ends, and all so arranged 30 as to be driven by two continuous belts, whereby cog-wheels, idlers, and pinions may be dispensed with and a steady and uniform motion secured, substantially as and for the purpose set forth.

35 2. In a continuous train of rolls wherein box-grooves are used, the rolls having alternately deep and shallow grooves, so that more than one half of the box will be in one roll and less than one half in the other roll, and so arranged

that the deep groove or portion of the box 40 shall alternate from the bottom to the top roll of each succeeding pair, whereby the fin formed will be rolled into the edge of the metal at each succeeding pass.

3. A journal-box for the top roll of rolling- 45 mills, said box formed in a single piece and having the housing-cap integral therewith, whereby the rolls may be lined up by inserting liners between the housing-cap and housing, substantially as and for the purpose speci- 50 fied.

4. A continuous train of rolls having its main driving-shaft attached to the rolls which are required to be rotated at the greatest velocity, and having a pulley or pulleys attached to the 55 end or ends of the roll-bearings, substantially as set forth, whereby the greatest strain is concentrated at or near the driving-power.

5. A continuous train provided with a series of pairs of rolls, each pair of which from the 60 first have an increased diameter as compared with the preceding set, and each set having pulleys decreasing in diameter as the rolls increase in diameter, substantially as and for the purpose set forth.

6. A continuous train of a series of pairs of rolls having pulleys mounted on the roll-spindles, and so arranged with relation to each other as to admit of communicating the power alternately from the bottom roll of one pair to 70 the top roll of the succeeding pair, whereby all the rolls may be rotated in the proper direction without the use of idlers.
